CONTACTLESS VARIABLE RESISTOR
Robert J. Winter, 12 Crestwood Drive,
Avon, Conn. 06001
Filed June 21, 1965, Ser. No. 465,351
6 Claims. (Cl. 338—79)

The invention hereafter disclosed pertains to variable resistors of the general type known as potentiometers; and more particularly to a variable resistor utilizing a flexible wire or wire-like resistance element but not utilizing or comprising any sliding or brushing movable contact.

In the prior art there are disclosed variable resistors and potentiometers of divers constructions, in which instruments the terminal connections are made to ends of a length of resistance wire or other resistance element and to a contact member whose position relative to or along the element is variable whereby to vary the potential or resistance exhibited between the contact terminal and one or the other of the end terminal connections. All such potentiometers or variable resistors are characterized by a nonuniform variation of the electrical contact-resistance evidenced between the contact member and the resistance element as relative motion between the contact member and the element occurs incident to adjustment being effected. Such variation of contact resistance, in the form of irregular variations of the potential or resistance exhibited as noted, is in the trade designated by the term "contact noise." It is desirable to reduce such variation of contact-resistance or noise to the lowest possible values.

The present invention, by eliminating entirely the sliding or brushing contact-member of a variable resistor or potentiometer, eliminates the source of the above-mentioned undesirable "noise." According to the invention, the two physical ends of a resistance element are permanently connected to respective permanent first and second terminals, and the resistance exhibited between the first and second terminals is varied by effectively short-circuiting a desired variable extent of the resistance element disposed between the first and second terminals and thus by varying the extent of the resistance element not short-circuited. The noted result is accomplished by winding a desired extent of the resistance element from an insulation mandrel surface or form onto a highly conductive mandrel surface or form, and vice versa; one end of the conductive mandrel surface or form, for example, providing the second terminal, to which one physical end of the element is conductively secured, and a terminal connected to the other physical end of the element, on the insulation mandrel surface or form, providing the first terminal. Obviously, three terminals may be provided, if desired, by connecting the ends of the conductive mandrel surface to respective different terminals. However, since two of the three terminals thus provided would be at the same potential, there will ordinarily be no necessity for a third terminal. Preferably, and as herein illustrated in elementary exemplary form, the conductive mandrel surface or form is stationary and of elongate form such as a cylinder, and the insulation mandrel surface is rotatable around the axis of the conductive stationary member surface and is prevented from rotating about its own axis as it is rotated about the conductive form. The two mandrels or forms are arranged with their axes parallel, and may present uniformly helical winding formations or surfaces to receive the resistance element, or may, alternatively, present specially shaped winding formations or surfaces whereby a desired functional relationship is attained between rotation of the rotary mandrel surface and variation of exhibited resistance or potential drop.

2

Since neither of the two aforementioned mandrels partakes of rotation about its own axis, it is evident that no slip-ring or other sliding or brushing electrical connection is required. Since the rotatable mandrel merely rotates about the axis of the stationary mandrel but not on its own axis, a flexible electrical connection, such as a coil spring or a flexible wire connector, permanently connected at its one end to one end of the resistance element and at its other to a respective terminal, serves as a highly conductive path from the terminal to the end of the resistance element portion wound on the rotatable mandrel surface.

The preceding brief general description of the invention makes it evident that it is a prime object of the invention to provide a variable resistor of the wire or filament-element type that is devoid of a sliding or brushing contact member.

Another object of the invention is to provide a variable resistor adapted to be adjusted by rotation of a rotary actuator and which is totally devoid of effects such as are produced by sliding or brushing of a contact member on a resistance element.

Another object of the invention is to provide a rotary variable resistor in which all electrically active components are positively connected together whereby electrical noise incident to sliding of electrical contact means is completely obviated.

Other objects and advantages of the invention are hereinafter set forth or made evident in the appended claims and the following detailed descriptions of preferred exemplary embodiments of variable resistors according to the invention as illustrated in the accompanying drawings forming a part of this specification.

In the drawings:

35 FIGURE 1 is a view in elevation, to no particular scale, showing an elementary preferred construction of variable resistor according to the invention;

40 FIGURE 2 is a stepped or irregular sectional view of components of the variable resistor depicted in FIGURE 1, viewed as indicated by the arrows and stepped broken line 2—2 in FIGURE 1;

45 FIGURE 3 is a transverse sectional view of structure depicted in FIGURE 1, viewed as indicated by the arrows and broken line 3—3 in FIGURE 1;

50 FIGURE 4 is a transverse sectional view of structure depicted in FIGURE 1, viewed as indicated by the arrows and broken line 4—4 in FIGURE 1;

55 FIGURE 5 is a view in elevation, partly in section by removal of portions of parts to reveal details, to no particular scale, illustrating a modified form of exemplary variable resistor structure according to the invention;

FIGURE 6 is a sectional view showing structure depicted in FIGURE 5, viewed as indicated by arrows and broken line 6—6; and

60 FIGURE 7 is a fragmentary sectional view taken as indicated by broken line 7—7 of FIGURE 5, with portions of structure broken away to facilitate illustration of details.

65 Referring first to FIGURES 1 and 2, the preferred elementary exemplary variable resistor device, 10, according to the invention comprises principal supporting means in the form of a base 12 and upstanding posts 12a and 12b which may conveniently be formed integral with the base 12. Post 12a is arranged to support a stationary mandrel device 16 the functions of which are to provide a first and conductive winding surface upon which extents or lengths of a bare resistance element of wire-like form may be wound, and to short-circuit the convolutions or turns of the resistance element thereon wound. As shown in the preferred form, base 12 and post 12b are of metal, and mandrel device 16 is, as shown in its simplest form, a

metal member affixed at one end to post 12b from which it is insulated by an insulating bushing 14b and cooperating insulating washer 14w. As is evident, if post 12b is formed of insulation, the bushing and washer are not essential; and similarly, the mandrel device may be in a form providing conductive winding surface, as by a sleeve or wrapping of metal applied over an insulation bolt-like core, with an appropriate electrical connection of the conductive jacket to a terminal. Other modifications of structural features will be obvious in the light of the disclosure, but in the interest of brevity and clarity further description and explanation of the invention will be restricted to the simpler illustrative structures depicted in the drawings. The end of mandrel 16 next-adjacent to post 12b is used to support terminal means which include, in the illustrated example, a terminal clip 16t and clamping nuts 16w engaged with a screw thread provided on the end of the mandrel.

Rotatably mounted on the first or stationary mandrel device is a carriage device 18 whose function is to support a second elongate mandrel device with the axis of the latter generally parallel to that of the first mandrel device, and to rotate the second mandrel device about the first while maintaining the axes generally parallel. The second mandrel device provides an insulative (nonconductive) wrapping surface upon which extents of the bare resistance element may be wound. The rotary carriage device 18 comprises end members illustrated as being in the form of plates 18a and 18b both rotatably supported, as shown, on mandrel device 16. The carriage device further comprises means rigidly connecting together the plates 18a and 18b, the connecting means as shown being spacing bars 18c, 18d and 18e (FIGURE 3) affixed at the ends to respective ones of the plates. As shown, the spacing bars are formed with reduced ends that are fixed into complementary apertures or bores formed in the end plates. Rigid connection is effected by suitable means, such as by adhesive or by screw-threads in case the bars and plates are of insulation, as shown; or brazing or the like in case those members are metallic.

The previously mentioned second mandrel device as shown in the preferred form in the drawings comprises an elongate mandrel 20 having an elongate nonconductive winding surface which preferably is grooved for reception of turns of the resistance element 22. In the preferred form of the invention the resistance element is a simple bare wire of resistive material. Mandrel 20 is provided with a portion of reduced diameter at one end, which portion is slidable and rotatable in a radially-extending slot 18s (FIGURE 3) provided in plate 18a. Slot 18s is preferably closed, as it is when formed as a radially elongate aperture in plate 18s. At its other end, mandrel 20 is arranged in similar manner to be rotatable and radially slidible in a similar closed slot or aperture provided in plate 18b. The rotary mandrel 20 is prevented from excessive or undesired longitudinal shift or displacement in the carriage device 18 by suitable restraining means such as insulation collars 20c and 20d (FIGURE 2) that are secured to the mandrel at respective opposite faces of plate 18b and slidably engage respective faces of the plate.

The carriage device 18 is arranged to be rotated about the axis of mandrel 16 by application of driving effort or force to the extended end 20e of mandrel device 20, by the bifurcated end of a crank or driver 24 which is rotatably supported on and by a shaft 26 arranged in coaxial relationship with mandrel device 16 and adapted to be turned or rotated by any suitable driving means, such as, for example, a knob 28 affixed to the shaft. The shaft 26 is rotatable in bearing means here shown as a bushing 30 that is fixed in an aperture in post 12a, as illustrated in FIGURES 1 and 2.

So that the flexible resistance element 22 may be wound off fixed mandrel device 16 onto rotary mandrel device

20, and vice versa, incident to rotation of carriage device 18, and to permit permanent nonbrushing electrical connection to that end of the resistance element carried by the rotary mandrel device 20, the latter must be restricted or prevented from rotating relative to base 12 during rotation of the carriage device 18. To the latter end or objective, rotation-restricting means comprising an oscillatory governor 32 are provided. The governor 32 as illustrated includes an upstanding pin 32p that is slidably received in a transverse bore formed through collar 20d and mandrel device 20, the pin being joined to, or formed as an integral upstanding extension of, an oscillatory arm 32a that is mounted for restricted oscillation on a bearing surface provided by a bearing screw 32b (FIGURE 1). The bearing screw is fixedly supported and is accommodated by a tapped hole provided in a pedestal formed on base 12 as indicated in FIGURE 1. Thus as carriage device 18 is rotated, collar 20d is carried around the axis of mandrel 16 and oscillates along the upstanding pin 32p and in turn moves pin 32p to and fro laterally of base 12, oscillating arm 32a in the process. A slotted connection with bearing screw 32b permits the necessary compound oscillation of arm 32a. As will be evident, when mandrel device 20 is thus driven or carried around mandrel device 16, the resistance element will be unwound from the winding surface of one of the two mandrel devices and concurrently wound upon that of the other. The winding surfaces, here shown as grooves, must be complementary whereby payoff and take-up of the element occurs without creation of undue slack or tension in the element.

Permanent or nonbrushing electrical connection with that end of element 22 that is secured to mandrel device 20 is effected by passing one end of the element through a diagonal bore formed through the mandrel device (as indicated by dotted lines in FIGURES 1 and 2), and conductively and mechanically securing the element-end to the end of a flexible insulated conductor 34 (FIGURES 2 and 4) one end of which is anchored to collar 20d. The other end of conductor 34 is attached to a terminal 36 affixed to base 12 as indicated. Thus it is evident that as the carriage device 18 is rotated, collar 20d is carried around a circular path orbiting shaft 26, but is prevented from rotating relative to base 12 by governor pin 32p, and hence conductor 34 is merely flexed during multiple-turn rotation of the carriage device. Since the remote or other end of the resistance element is connected directly to the conductive surface of fixed mandrel device 16, there exists a continuous brushless electric path between terminal 36 and terminal 16t, the electrical resistance of which path is varied by short-circuiting of a greater or lesser extent of element 22 as the element is wound onto, or off of, the conductive surface of mandrel device 16.

To accommodate slight variations or nonconformities in the winding surfaces of the two mandrel devices, mandrel device 20 is permitted to travel radially in carriage device 18, to an extent restricted by the ends of the radial slots in plates 18a and 18b in which the mandrel device 20 is supported. To maintain the mandrel device 20 against undesired radial travel and to keep taut the reach of the resistance element extending between the two mandrel devices, shaped wire spring devices 18p (FIGURE 3) and 18q (FIGURE 1) are provided. The spring devices preferably are twins, and as depicted in FIGURE 3, are formed to each have a free end portion pressing against mandrel device 20, an intermediate portion stressed around spacing bar 18e, and an anchored end turned around bar 18d. Thus mandrel device 20 is resiliently pressed outwardly in the slots in the end plates of the carriage, but may travel inwardly as may be required. As is evident the spring constants of the springs 18p and 18q are such that a desired degree of tension is created and maintained in the resistance element 22.

A modified form of variable resistor according to the invention is illustrated in FIGURES 5, 6 and 7. Therein

a stationary conductive mandrel 116 provides a tapered conductive winding surface of circular cross-section, preferably grooved as shown, and supported by and insulated from an open rectangular frame 111 formed of flat strip-like material. A rotary mandrel 120 is disposed with its axis parallel to that of mandrel 116, and is provided with a tapered nonconductive winding surface, also preferably grooved and of circular cross-section and with taper complementary to the taper of the stationary mandrel. As indicated, the tapers are similarly directed, whereby the extent of flexible resistance element 122 that is unwound from either of the mandrels during any rotation of the carriage is equal to that wound onto the other mandrel. Fixed mandrel 116 is provided with terminal connection means as shown and in fashion similar to the previously described embodiment of apparatus.

Rotary mandrel 120 is arranged to be driven about mandrel 116 in both directions by being carried at one of its ends in a slotted crank arm 124, and by being carried at its other end in a radially slid able cup 118c disposed in a slot in a rotary member 118 which is held captive on but permitted rotation around a bearing member 116b disposed on the anchored end of mandrel 116, as depicted. The end of mandrel 120 is rotatable in the guide cup 118c, and the cup is spring-urged outwardly by a leaf spring 118s affixed at one of its ends to the member 118 as indicated in FIGURE 7. At its driven end mandrel 120 is affixed in a shaped collar 120c, and extends through a radially elongate aperture in crank arm 124 in which it is held captive by nut and washer means as indicated in FIGURE 5. The collar 120c is stressed or outwardly urged by means including a leaf-spring 124s as indicated in FIGURE 6, so as to cooperate with spring 118s to maintain under tension the reach of resistance element 122 between the two mandrels.

Crank arm 124 is affixed to the interior end of a rotary driver shaft 126 that is journaled in a bushing 130 that is mounted in an accommodating aperture in frame 111, as indicated in FIGURE 5. Shaft 126 is retained in proper position by retainer rings 126r disposed in accommodating annular grooves in the shaft, at respective ends of bushing 130. Any suitable controllable source of torque may be used to rotate shaft 116 and thereby cause short-circuiting of more or less of element 122 by the conductive winding surface of mandrel device 116; and as shown, a manually-operable knob 128 is shown as exemplary means for the indicated purpose.

Rotation of mandrel 120 relative to frame 111 and base 112 to which the frame is fixedly mounted, is prevented by means including an oscillatory governor which comprises a pin 132p which is slidably received in aligned bores extending through collar 120c and mandrel 120 as indicated in FIGURES 5 and 6, pin 132p being integral with or secured to an oscillatory arm 132a suitably secured to frame 111 by means including a pivot bearing 132b. Arm 132a is slotted for compound oscillation on bearing 132b.

Electrical connection to the end of element 122 carried on movable mandrel 120 is by way of an anchor screw 120s secured in insulation collar 120c and to which one end of element 122 is secured after being drawn through a transverse anchoring bore formed in the mandrel, as shown in FIGURES 5 and 6. A flexible insulated conductor 134 extends between anchor screw 120s and an insulated terminal 136 affixed on base 112 as indicated in FIGURE 6. Electrical operation of the modified form of variable resistor depicted in FIGURES 5, 6 and 7 is substantially the same as that of the principal embodiment of the invention, except that due to the specially-shaped mandrels, the variation of resistance per degree of revolution of the driving means is made to follow a nonlinear mathematical relationship. As is evident, the taper of the mandrels may be varied to provide many other relationships.

While very elementary constructions of the variable

resistor have been illustrated and described so as to more easily and simply portray the principles of the invention, it will be evident to those skilled in the art that refinements and modifications may be made, all within the true spirit and scope of the invention. Accordingly it is not desired that the invention be restricted to the details of the illustrated exemplary elementary forms, but only as defined and restricted by the appended claims.

I claim:

1. A variable resistor device comprising:

first means, including supporting means and an elongate fixed mandrel device fixedly supported thereon, said fixed mandrel device defining a first axis and having a conductive surface providing a first winding surface upon which a flexible conductor may be wound in numerous turns or convolutions;

second means, including a carriage supported by said first means for rotation about the said first axis, and means for causing rotation of said carriage about said first axis through numerous revolutions;

third means, including an elongate rotary mandrel device rotatably supported by said carriage for rotation about a second axis parallel to said first axis, said rotary mandrel device having an insulated surface providing a second winding surface complementary to said first winding surface and upon which a flexible conductor may be wound;

fourth means, including means connected to said first means and to said rotary mandrel device, for preventing rotation of said rotary mandrel device relative to said supporting means and permitting rotation of said rotary mandrel device relative to said carriage incident to rotation of said carriage about said first axis;

and fifth means, including an elongate bare flexible resistive element wound in part upon said conductive first winding surface and fixedly connected thereto, and in part wound upon said insulated second winding surface and adapted to be wound from either of said winding surfaces to the other incident to rotation of said carriage, said fifth means further including a first fixed electric terminal means fixedly connected to said first winding surface, and a second fixed electric terminal means and a flexible insulated conductor fixedly connected at one end to said flexible resistive element wound on said rotary mandrel device;

whereby the effective electrical resistance exhibited between said first and second fixed electric terminal means may be varied without brushing or wiping contact and by rotation of said carriage.

2. A resistor device as defined in claim 1, in which said first winding surface is provided by a groove disposed along a longitudinally curved surface of substantially cylindrical cross-section whereby increments of the length of the groove bear a predetermined nonlinear mathematical relationship to degrees of rotation of said carriage, and in which said second winding surface is complementary to said first winding surface whereby to take up and pay off said flexible resistance as required to properly accommodate the latter incident to rotation of the carriage, whereby variation of resistance exhibited between said terminals varies in accord with a predetermined nonlinear mathematical relationship relative to degrees of rotation of said carriage incident to rotation of said carriage.

3. A resistor device as defined in claim 1, in which said fourth means includes an oscillatory member pivoted to said first means and having a rectilinear arm extending through a transverse bore formed through said rotary mandrel device, thereby preventing rotation of said rotary mandrel device relative to said first means while permitting rotation of said carriage and second mandrel device around said first axis to cause unwinding and winding of said resistive element relative to said first and second mandrel devices whereby to vary the extent of

said resistive element short-circuited by said conductive winding surface to vary the electrical resistance exhibited between said terminal means.

4. A variable resistor device as defined in claim 1, in which said carriage device includes first and second end members rotatable on said third means and spacing bar means rigidly connecting together the end members, and in which said end members are provided with slots carrying respective end portions of said rotary mandrel device to permit increase and decrease of spacing between the fixed and rotary mandrel devices, and resilient means tending to move the rotary mandrel away from the fixed mandrel.

5. A variable resistor device adapted to exhibit between fixed terminals thereof any finite value of resistance between determined minimum and maximum values without movement of a contact on a resistance element, said resistor device comprising:

first means, including supporting means and fixed terminals supported thereon;

second means, including an elongate bare flexible resistance element;

third means, including a fixed mandrel with a conductive winding surface thereon, and a second mandrel with an insulated surface thereon, and means for relatively rotating one of said mandrels around the other and for preventing rotation of either of the mandrels relative to said supporting means, whereby to wind portions of said resistance from either of said mandrels onto the other; and

fourth means, including means whereby one of said terminals is positively connected to said conductive winding surface, and means including a flexible insulated conductor interconnecting the other of said terminals and a portion of said resistance element wound upon said second mandrel;

whereby incident to relative rotation of said mandrels portions of said resistance element are transferred by winding onto one of said mandrels from the other thereof to change the extent of said element wound upon said conductive winding surface to thereby change the resistance exhibited between said terminals.

6. A variable resistor device adapted to exhibit between fixed terminals thereof any finite value of resistance be-

10

tween a determined highest resistance value and a determined lowest resistance value, without interruption of a continuous electrical path between the terminals and without movement of a contact on a resistance element, said variable resistor device comprising:

supporting means, and stationary electric terminals supported by the supporting means;

elongate stationary means fixedly supported by said supporting means and presenting a winding surface, said elongate stationary means defining an elongate axis;

elongate rotary means having a winding surface and an elongate axis extending generally in the same direction as that of said elongate stationary means;

means for rotating said rotary means;

an elongate flexible bare resistance element having one end fixedly connected to a first one of said terminals and wound in part on each of said winding surfaces;

one of said elongate stationary and elongate rotary means having a highly conductive winding surface effective to short-circuit turns of said resistance element wound thereon; and

flexible conductor means connecting the second one of said terminals to the end of the portion of said resistance element wound on said winding surface of said elongate rotary means,

whereby upon rotation of said rotary means an extent of said resistance element is unwound from one of said winding surfaces to the other winding surface and the extent of said resistance element short-circuited by said conductive winding surface is varied and the resistance exhibited between said terminals is varied.
